BOILER COMPOUND DISPENSER

Joseph Woods Riley and Matthew Turton,
Guatemala City, Guatemala

Application August 1, 1938, Serial No. 222,543

2 Claims. (Cl. 210—39)

This invention relates to what may be termed a "boiler compound dispenser", the device being designed particularly for feeding a water-treating compound or solution to water being fed to a locomotive boiler.

In accordance with the present invention a device of the character described is provided for connection either directly to the locomotive injector or to the locomotive feed water heater pump at the vacuum side thereof whereby the compound or solution will be drawn into the injector or the pump as the case may be to there commingle with the water being fed to the boiler.

A further object of the present invention is to provide a device of the character mentioned which is substantially automatic in operation requiring neither attention nor adjustment.

It will also be found in actual practice that the device will operate with equal efficiency on stationary boilers or any other type of boiler.

The invention together with its objects and advantages will best be understood from a study of the following description taken in connection with the accompanying drawings wherein:

25 Figure 1 is a view of the device with the compound reservoir tank and sight glass associated therewith shown in section.

Figure 2 is a sectional view through a chamber-forming assembly hereinafter more fully referred to.

Figure 3 is a sectional view taken substantially on the line 3—3 of Figure 2.

Figure 4 is an elevational view of a window glass for the sight feed chamber shown in Figure 2.

Figure 5 is a sectional view through a window gasket and

Figure 6 is a view taken substantially on the line 6—6 of Figure 1.

40 Referring to the drawings by reference numerals it will be seen that in accordance with the invention there is provided a suitable tank 5 that may be conveniently mounted on the locomotive and is adapted to contain the water treating compound. The tank 5 at the top thereof is provided with a filling opening 6 for which a hinged door or closure 7 is provided, the door 7 being provided further with a vent opening 8 as shown.

50 Also in order that one may readily ascertain the level of the compound or solution within the tank 5 there is provided for the tank a sight tube assembly 9 which includes a sight tube 10 of glass, or other transparent material, suitably connected with upper and lower fittings 11 and 12 that are

tapped into one end wall or header plate of the tank 5 and are secured to said wall of the tank through the medium of jamb nuts 13 as shown.

Extending into the tank 5 through a suitable opening provided therefor in the top of the tank 5 is a suction tube 14 which at its inner end is bent into a substantial U, and at said end is provided with a screened inlet 15.

At the outer end thereof the suction tube 14 is connected through the medium of a coupling 16 with a substantially L-shaped nozzle 17.

The nozzle 17 is tapped into the wall of a substantially cylindrical sight-feed chamber 18. The nozzle 17 is provided with a removable tip 19 through which the solution drawn into the chamber 18 through the tube 14 from the tank 5 enters the chamber 18 in jet form.

The chamber 18 is provided at the opposite ends thereof with sight windows, each sight window including a window glass 20 that has a diametrically enlarged end 21 that is in abutting engagement with an internal annular shoulder 22 provided therefor inwardly from an end of the chamber 18; an end 23 of reduced diameter, and a tapered intermediate section 24.

Sleeved on the sections 23 and 24 of each window glass 20 is a packing ring 25 of rubber or other suitable material and having its bore, at one end thereof, flared as at 26 to conformably accommodate section 24 of the window glass.

The glass 20 and packing ring 25 are held in position within the chamber 18 through the medium of an aforementioned internal shoulder 22 and an annular follower 27 that threads into the end of the chamber as clearly shown.

In connection with the above, and as clearly shown in Figure 2, the sight window assembly is duplicated at each end of the chamber 18.

Tapped into the chamber 18 intermediate the shoulder 22 is one end of a pipe section 28. Suitably connected to said end of the pipe section 28 is an intake nozzle 29 provided with a suitable and removable tip 30. At the opposite end thereof the pipe section 28 is connected through the medium of an elbow or other suitable fitting 31 with a nipple 32 a portion of which only is shown in the drawings and which nipple extends from the vacuum side of the injector or pump of a water feed system of a locomotive boiler.

It will thus be seen that in actual practice when the injector or pump of the feed water system of a locomotive boiler is in operation the compound-contents of the boiler 5 are, by vacuum, drawn into the tube 14 through the screen inlet 15 thereof passing through the tube and discharging 55

through the nozzle 17 into the sight-feed chamber 18. From the chamber 18 the compound is drawn into the injector or pump as the case may be, passing from the chamber 18 through the 5 nozzle 29, pipe 28 and nipple 32 thereby supplying the water-conditioning compound to the water being fed to the locomotive boiler.

In actual practice it will be found that the device will operate to feed the compound into the 10 boiler in correct proportion to the water being fed to the boiler with the result that the boiler will be kept free from scale and consequently less fuel will be required for the efficient operation of the boiler.

15 The device will also be found, in actual practice, to be a labor saver, to be substantially fool-proof having practically no moving parts to get out of order; will permit injectors and boiler checks to be worked longer periods without 20 shutdown, will lengthen the life of boiler flues, fire boxes, etc.; eliminate the expensive installation of water-treating stations and will not require mechanical knowledge for the control and operation thereof.

25 It is thought that a clear understanding of the construction, utility, advantages and operation of an invention of this character will be had without a more detailed description.

Having thus described the invention what is 30 claimed as new is:

35 1. A device for use in connection with the feed water system of boilers for feeding a water-treating compound to the water being supplied to such boiler, said device comprising a receptacle for the compound, a sight feed chamber remote from 40 said receptacle, a suction line extending from the receptacle to said chamber, a nozzle at the discharge end of the suction line extending into the chamber through an upper portion thereof, a second suction line extending from the chamber and adapted to be connected with the in-

jector of such system at the vacuum side of said injector, said second suction line having a part extending downwardly through the chamber to a point adjacent the bottom of the chamber and a tip connected with the lower end of said part 5 and having a reduced bore therein.

2. In a boiler compound dispenser, a chamber including a horizontally arranged tubular member having internal annular shoulders spaced apart and spaced from the ends of the tubular 10 member, said ends of the tubular member being internally threaded, a transparent plug fitting in each end of the tubular member, each plug having an enlarged inner end resting against one of said shoulders, a reduced cylindrical outer 15 end and a tapered intermediate part connecting the reduced outer end with the enlarged inner end, an annular gasket fitting around the reduced outer end of each plug with its inner end bearing against the tapered portion, an annular 20 follower exteriorly threaded to engage the internal threads at each end of the tubular member with the inner end of the follower engaging the gasket, a supply pipe having a portion entering the tubular member at an angle in the upper 25 portion of the tubular member and between the shoulders, a nozzle extending into the tubular member and connected with said part of the supply pipe, an outlet pipe entering the top part of the tubular member between the shoulders, a 30 tubular member connected with the inlet end of the last-mentioned pipe and extending to a point adjacent the lower side of the tubular member, and a tip in the lower end of the last-mentioned tubular member and terminating in spaced relation to said lower side of the first-mentioned tubular member, and means for connecting the discharge pipe with a suction producing device. 35
